FIG. 1 is a perspective view of a modular building block unit showing my new design;

FIG. 2 is a top plan view of the modular building block unit shown in FIG. 1;

FIG. 3 is a bottom plan view of the modular building block unit shown in FIG. 1;

FIG. 4 is a perspective view of a modified form of the modular building block unit shown in FIG. 1;

FIG. 5 is a top plan view of the modular building block unit shown in FIG. 4;

FIG. 6 is a bottom plan view of the modular building block unit shown in FIG. 4;

FIG. 7 is a perspective view of another modified form of the modular building block unit shown in FIG. 1;

FIG. 8 is a top plan view of the modular building block unit shown in FIG. 7;

FIG. 9 is a bottom plan view of the modular building block unit shown in FIG. 7;

FIG. 10 is a perspective view of another modified form of the modular building block unit shown in FIG. 1;

FIG. 11 is a top plan view of the modular building block unit shown in FIG. 10; and

FIG. 12 is a bottom plan view of the modular building block unit shown in FIG. 10.

My invention is characterized by the provision of a rectangularly shaped building block unit having at least one core extending therethrough and provided with pairs of juxtaposed projections and recesses on at least one of its side faces.

I claim:

The ornamental design for a modular building block unit, as shown and described.
